UNITED STATES PATENT OFFICE.

GEORGE HEGEMAN HART, OF WEST HARTFORD, CONNECTICUT.

ELECTRIC SWITCH.

Application filed January 16, 1924. Serial No. 686,510.

The object of the present invention is to provide an electric switch having various features of novelty and advantage.

More particularly, an aim of the invention is to provide an electric switch of improved construction, wherein damage to or destruction of the contact members, owing to the contacts pounding or improperly striking one another when brought into engagement, and to arcing when the circuit is broken, is substantially eliminated. Also, to provide a switch which is characterized by its simplicity and cheapness in construction, its durability, and its efficiency in operation.

15 In accordance with the present invention, the arrangement of the switch is such that the switch unit (or units) is free to adjust itself to, and is held at all times in proper relation to, the fixed contacts; and thus inaccuracies in the parts, for instance such as result from the warping or distortion when molding the porcelain base, are automatically taken care of, which means that a lesser degree of precision and, therefore, less work 20 and expense are required in manufacturing the parts. The switch unit is held in proper relation to the terminals or fixed contacts by the terminals themselves, in such manner that there is no excessive binding or rubbing 25 action between the parts; and the construction of the switch unit is such that arcing is reduced to a minimum.

Other objects will be in part obvious and in part pointed out hereinafter.

30 The invention accordingly consists in the features of construction, combination of elements and arrangement of parts which will be exemplified in the construction hereinafter set forth, and the scope of the application 35 of which will be indicated in the appended claims.

In the accompanying drawings, I have shown my improvements incorporated in a switch, the switch unit (or units) of which 40 may be rotated in either direction to make and break the circuit, but it is to be understood that this showing is by way of illustration only, it being obvious that my improvements may be incorporated, either 45 singly or severally, in switches other than the sort herein disclosed, and that my improvements are susceptible of various modifications, changes and embodiments.

In said drawings:

50 Figure 1 is a sectional view of my improved switch with the cover removed;

Fig. 2 is a horizontal sectional view taken substantially on line 2—2 of Fig. 1;

Fig. 3 is a horizontal sectional view taken on line 3—3 of Fig. 1;

Fig. 4 is a detail view showing, on an enlarged scale, parts of one of the switch units;

Fig. 5 is a view similar to Fig. 1, but showing another embodiment; and

Fig. 6 is a view showing parts of the switch unit of Fig. 5 in section, and parts in perspective.

Referring to Figs. 1 to 4, inclusive, of the drawings, 10 designates a base of suitable insulating material, such as porcelain. Carried by the base are suitable fixed terminal elements or contacts, the number of which will depend upon the requirements. In a single pole switch, there may be two such terminals. In the illustration of Figs. 1 to 3, there is shown a double pole switch and, therefore, two pairs of terminals are provided. The terminals of one part are designated by the numeral 11, and those of the other pair, which are at right angles to and at a higher elevation than those of the first pair, are designated by the numeral 12. Associated with the respective pairs of fixed contacts are the switch units *a* and *b*. These units are so constructed and associated with the member by means of which they are rotated and with the fixed contacts, that they are free to adjust themselves with respect to the fixed contacts, as hereinafter described more in detail. By way of example, I have shown the member, by means of which the switch unit, or units, is, or are, rotated, as comprising a driving element 15 operatively connected in such manner to a switch spindle 16 that, when this spindle is turned by rotating the handle 17, the driving element 15 and the switch units associated therewith are thrown with a quick or snap movement. It is to be understood that this arrangement is shown in the drawings by way of exemplification.

The spindle 16 is journalled in a bearing 18 in the base 10, and has a handle 17 fixed to its outer end. The handle may be fixed against rotation on the spindle by a projecting arm 19 secured to the spindle and engaging in a recess in the under face of the handle. Secured to, so as to rotate with, the spindle is a spring lever 20 which is positioned within the driving element 15. The latter is in the form of a yoke or an invert-

ed U, having its lower ends secured to a guide plate 21 in which is mounted, for radial movement, a catch plate 22 adapted to cooperate with a stop plate 23 secured to the base 10. The construction of the stop plate and catch plate is similar to that illustrated in the patent to Smart and Gates, No. 1,409,146, dated March 7, 1922, and, therefore, is not shown in detail in the present instance. Coiled about the spindle 16, and having its ends straddling the spring lever and one leg of the member 15, is spring 24. It will be understood that the handle may be turned, step by step, in either direction. When the handle is turned, the spindle 16 and the spring lever 20 turn therewith, thereby placing the spring 24 under tension until the catch plate is released from the stop plate and then the spring throws the driving element 15 and the switch units associated therewith with a quick or snap movement. The catch plate re-engages the stop plate to stop the switch units in their new indexed positions.

In the present instance, each of the switch units includes a pair of insulating disks 30 maintained in spaced apart relation by an insulating washer 31 of lesser diameter, and a conducting member or switch plate 32 located on the outside of each disk 30 and having its ends bent or turned over so as to extend into the groove or channel 33 between disks 30. The groove or channel 33 in the periphery of each switch unit, and which groove receives the fixed contacts, is preferably continuous and is of slightly greater width than the thickness of the fixed terminals so that there is sufficient clearance to permit the units to accommodate themselves to the fixed terminals. The conducting members or switch plates 32 may be of any suitable shape, depending on the adopted construction of other parts. Each of them is here shown, by way of example, as comprising a plate having diametrically opposite fingers or arms 34, the ends of which are turned over so as to project into the groove 33. The disks are suitably cut away to accommodate the over turned fingers 34, in the present instance, the disks being slotted as at 35 for this purpose. Preferably, the switch plates 32 are bowed or bent, as shown in Fig. 4, before they are secured in place, so that when they are fastened to the disks 30, the fingers 34 of the plates will be under tension, i. e., are urged inwardly of the groove 33. The parts of each unit are secured together in any desired manner as, for instance, by rivets 36. Each unit is provided with a central opening 37 of such size as to permit of rotation of the spring lever 20, and this opening has diametrically opposite notches 38 which slidably receive, as most clearly shown in Figs. 2 and 3, the legs of the driv-

ing member 15. Preferably, there will be a slight clearance between the legs of the driving member 15 and the sides of the notches 38 to permit of very slight tilting action of the units relative to the driving member so that the units may accommodate themselves to the fixed contacts.

The switch illustrated in Figs. 5 and 6 is like that of the preceding embodiment except that the switch unit is of somewhat different construction. Referring to these figures, it will be seen that the unit has disks 30, a spacing washer 31 therebetween, and a switch plate 32 associated with each disk. These parts are mounted on a bushing 50 having flanges 51 and 52 at its respective ends, and diametrically opposite, longitudinally extending slots or grooves 53, the latter of which accommodate the legs of the driving member 15. Each plate 32 has a non-circular opening in which closely fits a lining washer 54 adapted to receive the bushing. The plates 32 are insulated from the flanges 51 and 52 by rings 55 which also serve to hold the lining washers in place within the plates. The disks 30, the washers 31 and 54, and the rings 55 are of insulating material. These members are respectively provided with diametrically opposite notches 30^a, 31^a, 54^a, and 55^a adapted to register with the slots 53 of the bushing and to receive the legs of the member 15. If desired, a metal washer 56 may be interposed between the flange 52 and ring 55, and may have notches 56^a to receive the member 15. The parts are slipped, in the sequence shown in Fig. 6, onto the bushing and are then secured against withdrawal by turning over the end of the bushing, thus forming the flange 52. Owing to the engagement of the legs of the member 15 in the slots 53 of the bushing, and in the notches 30^a, 31^a, 54^a and 55^a, these parts rotate as a unit when the switch is operated. This arrangement is a very simple and economical one; the parts may be cheaply made and assembled, and the switch plates are properly held and suitably insulated.

From the foregoing description taken in connection with the drawings, it will be understood that the switch units are independently connected to the driving member 15 against rotary movement, but they are not fixed thereto against axial movement. The fixed contacts extend into the continuous grooves 33 in the switch units and thus hold these units at the proper elevation relative to the fixed terminals. In one manner of speaking, the switch units float or ride freely in their rotary movements on the fixed contacts, but as these units are relatively light in weight, there is substantially no rubbing and practically no drag between the units and the fixed contacts when the units are rotated. The units are

also capable of a slight tilting action so that, in the event one of the terminals is slightly out of alignment with another one, or is canted, the switch unit may self-align itself with respect to these contacts. Since the fixed contacts support the switch units in proper position, it will be readily seen that the spaces between the fingers 34 of the switch plates properly register with the fixed terminals, and thus when the switch is snapped, there will be no "pounding off" of the switch elements. My improved switch may be manufactured at a relatively low cost owing to the fact that inaccuracies or errors in the dimensions or positions of the parts are automatically taken care of, since the units are free to accommodate themselves to the fixed contacts. For instance, porcelain bases cannot be molded to close dimensions, and bases made in the same mold will vary one from the other. With the present arrangement, it is not necessary to true up the bases so that they are uniform and within predescribed close dimensions. Also, it is not necessary to manufacture the other parts with the same degree of accuracy as would be the case were the switch units held in given elevations by means other than the fixed terminals which cooperate with the respective units.

It will be noted further that since all portions of the conducting plates of the switch units, except those portions which are adapted to directly engage the fixed contacts, are located on the outside of the disks 30, arcing, when the switch is broken, is reduced to a minimum. Thus, the switch, as compared to its size, is capable of being used on relative high voltages.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In an electric switch, fixed contacts,

and a switch unit including a circumferentially grooved insulator and a switch plate fixed on the outer surface of said insulator and having its ends extending into said groove, said fixed contacts engaging in said groove and maintaining said unit in proper relation to said fixed contacts.

2. In an electric switch, fixed contacts, and a switch unit including a circumferentially grooved insulator and a pair of fixed plates one on the outside face of each insulator and each having its ends extending into said groove, said fixed contacts engaging in said groove.

3. In an electric switch, a spindle, a spring lever connected thereto, a driving member about said spring lever, a spring about said spindle and cooperating with said spring lever and driving member, and a switch unit having a central opening accommodating said spring and lever and having notches slidably receiving said driving member.

4. A switch unit including an insulator having a circumferential groove provided with slots in its walls, and switch plates on the outer faces of said insulator and having over-turned ends projecting through said slots and into said groove.

5. A switch unit including an insulating disk, and a switch plate secured to one face of said disk and having overturned ends projecting beyond the opposite face thereof, said plate being secured to said disk under stress.

6. A switch unit comprising an insulator having a circumferential groove, and resilient plates secured to the outer faces of said insulator and having their ends projecting into said groove, said switch plates being normally bowed but held down in a flat-wise condition and under stress against said disks.

7. A switch unit for an electric switch including a bushing having diametrically opposite longitudinally extending slots and flanges at its opposite ends, a pair of disks about said bushing, a spacing washer between said disks, a switch plate associated with each disk and having a non-circular opening, washers fitting in the non-circular openings of said switch plates, and insulating rings between said switch plates and flanges, said disks, washers and rings having diametrically opposite notches adapted to register with the slots of said bushing.

GEORGE HEGEMAN HART.
